(57) **CLAIM**

I claim the ornamental design of a combination pendant and lapel pin for a tie or lapel, as shown.

DESCRIPTION

FIG. 1 is a front elevational view of a combination pendant and lapel pin for a tie or lapel showing my new design;
FIG. 2 is a left elevational view thereof;
FIG. 3 is a right elevational view thereof;
FIG. 4 is a rear elevational view thereof;
FIG. 5 is a top view thereof; and,
FIG. 6 is a bottom view thereof.
